UNITED STATES PATENT OFFICE.

FRANCIS ALLEN LAZENBY, OF BALTIMORE, MARYLAND.

BOBBIN-WINDING MACHINE.

Application filed May 21, 1926. Serial No. 110,796.

This invention relates to an improved machine for winding double head bobbins.

One object of the invention is to provide an improved machine wherein the empty or partly empty bobbins are automatically fed from a hopper or rack to a chuck, or equivalent device, by which the bobbin is revolved to wind the yarn thereon, and during the winding there is a reciprocating movement between the 10 yarn and bobbin whereby to distribute the yarn over the bobbin. When the yarn is wound to the desired diameter, automatic means are provided to cut the yarn, discharge the filled bobbin and feed another empty or 15 partly empty bobbin to the chuck.

Other objects and advantages, such as discharging a bobbin in case the yarn breaks and supplying a new bobbin, will be pointed out as the description proceeds.

20 The invention is illustrated in the accompanying drawings, wherein,—

Fig. 1 shows the machine in side elevation.

Fig. 2 illustrates the same in front elevation.

25 Fig. 3 shows one of the winding units in side elevation as the same would appear if viewed on the line 3—3 of Fig. 2.

Fig. 4 illustrates the empty bobbin transfer devices in perspective.

30 Fig. 5 shows an enlarged vertical cross-sectional detail through the machine,—the section being taken on the line 5—5 of Fig. 2 looking in the direction of the darts.

Fig. 6 illustrates in a diagrammatic perspective the several cams and the devices actuated thereby.

Fig. 7 shows two of the winding units in top or plan view.

Fig. 8 illustrates one of the units in front 40 elevation.

Fig. 9 shows one of the units in top or plan view with the chuck-parts in the released position to discharge a filled bobbin, and

Fig. 10 illustrates a vertical sectional detail through the yarn guides to show how the 45 yarn is held as the cutter engages the same to cut it.

Referring to the drawings and particularly Figs. 1 to 4 thereof, the numeral 12, designates a base of any suitable construction, provided, in this instance and at the rear of the base with a suitable frame 13, which carries a platform 14, on which a series of vertical spindles 15 are sustained. These spindles 50 form supports for supplies of yarn 16 which

latter are to be drawn off and wound onto double-head bobbins such as are employed in various cloth-making machines.

Above the spindles the frame 13, sustains one or more horizontal shafts, in this instance three in number and designated 17—18 and 19 respectively. These shafts carry a plurality of guides 20 and the strands of yarn 16 are led from the supplies and passed around the said guides on their way toward 65 the bobbins.

At the front of the machine suitable standards 21 are provided which latter carry a horizontal rod 22, on which tension disks 23 are properly spaced whereby each strand is kept 70 under proper tension during the winding operation.

Cross-bars 24 are also employed in the present instance to connect the front standards 21 with the rear frame 13 whereby to produce 75 rigidity in the structure, and suitable brace bars, such as that shown at 25, serve the same purpose.

In the design and operation of my improved machine, I have elected to centrally locate 80 the driving and main actuating elements and to provide individual winding-units at opposite sides of the central driving elements so that a plurality of units may be operated from a single driving mechanism.

The number of winding units at each side of the single driving mechanism may vary, but in the present disclosure of my invention, I show two units at one side of the central mechanism, presuming that the same number 90 are arranged at the opposite side, but this is for illustrative purposes only in this particular instance.

On top of the base 12, and at the front corners I provide vertical bearing frames 26 and 95 between said frames, I also mount on the base a central frame or housing structure which includes two spaced-apart vertical bearing plates 27. The bearing frames 26 and the plates 27 form a supporting structure for certain shafts, bars and rods that extend horizontally but in an elevated position above the base.

A stationary flat bar 28 extends horizontally across and is secured at the front edge of the supporting structure and this flat bar, in addition to other uses, serves to tie the several vertical bearing frames and plates together.

The bearing-plates 27 are, in this instance, 110

spaced sufficiently to form a housing or frame-like structure for the main driving mechanisms from which the various parts of the machine are actuated.

6 These driving mechanisms include a horizontal shaft 29, on which a main pulley 30 is mounted,—the pulley being driven by a belt 31 that passes about the pulley of a motor 32. Of course, any suitable driving means for shaft 29 may be employed. At the side of the pulley 30, I provide a pinion 33, which is driven as the shaft 29 is revolved, and this pinion meshes with and drives a gear 34 on a short horizontal shaft 35.

15 The gear 34 meshes with and drives a gear 36, on a worm-shaft 38, said latter shaft carrying a worm 39 that drives a worm-gear 40. This worm-gear 40 is carried on shaft 41 which extends in a direction fore and aft of the machine or at right angles to the shaft 29. This shaft 41 may be termed a cam-shaft because it carries a series of cams which will presently be described, and the cams on this cam-shaft are constantly revolved.

20 At each end of the machine, I provide the vertical bearing frame 26 with a rearwardly-extending arm 42, (see Fig. 7) through which a horizontal supporting and tie-rod 43, extends from one end to the other of the machine. This tie-rod 43, also passes through the vertical bearing-plates 27, which give it additional support between its ends.

25 Another tie-rod 44, extends horizontally from end-to-end of the machine and is also supported by the vertical bearings 26 and 27. Both of the tie-rods 43 and 44 are stationary and have no movement.

The bearing 26 and the bearing-plates 27 are each provided with a bearing-head 45 in which a chuck-head or a head-stock 46 is mounted,—each head-stock being provided with a pulley 47, for the travel of a belt 48, that extends downwardly and passes around a pulley 49, on the horizontal pulley-shaft 29.

40 As the mechanisms coacting with each head-stock 46 are identical and there are a plurality of such stocks employed in the machine disclosed, a description of one will apply with equal effect to the others.

45 A tail-stock 50 coacts with each head-stock and each tail-stock is carried on a bracket 51. This bracket 51, has a rear bearing 52 that is loosely sustained on the tie-rod 44, and is provided with a forward bearing 53 that loosely 55 engages a horizontal reciprocating rod 54, which extends throughout the width of the machine.

50 It is to be understood that the rear rod 44 is simply a support on which the bracket 51 slides, whereas the rod 54 is a continuously reciprocating rod and will reciprocate through the front bearing 53 of the bracket when the latter is in the operating position with respect to the head-stock, which is during the winding operation. The reciprocating movement

however of this shaft 54 is utilized to restore the tail-stock to its normal winding position after it has been shifted to one side to release a filled bobbin and allow an empty bobbin to be supplied, as will presently be more fully explained. 70

Each tail-stock bracket 51 is provided with an arm 55 which extends horizontally in front of the tail-stock and toward the head-stock 46 and this arm carries a cutter blade 56 for a purpose that will also presently be explained. It is thus to be understood that any horizontal movement imparted to the tail-stock and its bracket 51 will also be imparted to the arm 55 and cutter blade 56. 75

Beneath the cutter-blade arm 55 there is provided a horizontally-extending trip-lever 57, which latter is pivoted at 58, to the upper side of the stationary bar 28. This lever will therefore swing in a horizontal plane. 80

One end of this lever 57 has a coiled spring 59 attached thereto so as to normally keep said end drawn toward the space between the two chucks or head and tail stocks. 85

The opposite end of this trip-lever 57 has a tapered edge 60 at its inner side while its outer side has a straight edge 61, which is in substantial vertical alinement with the vertical edge of the stationary bar 28 and both of these edges perform useful functions as will presently be explained. 90

Beneath the trip-lever 57 there is provided a pivoted trip-dog 62 which latter has a pointed trip-end 63, at one side of its pivot 64 and is also provided with a hook 65 at the opposite side of said pivot. 100

At the latter hook-end the dog also carries a pin 66 and a coiled spring 67 is attached to this pin and constantly draws the hook end inwardly and tends to project the trip-end 63 outwardly. 105

A trip-finger 68 is carried at one end of the trip-lever 57 and this finger (see Fig. 7) normally has position between the two chucks 46 and 50. The position of this trip-finger 68 is such that if it be pressed forwardly it will swing one end of the trip-lever forward with it, while the opposite end of this trip-lever will swing inwardly, as shown in the plan view of Fig. 9, and by swinging inwardly, the straight-edge side 61 of said lever will swing away from the vertical outer edge of the bar 28, as can be readily seen by comparing the positions of the lever 57 in Figs. 7 and 9. The purpose of this lever-movement 110 will also presently be explained. 115

By again referring to Fig. 7 of the drawing it will be seen that the hook 65 normally projects around and engages the side edge of the chuck bracket 51 and holds the tail-stock 50 of the chuck in the operating position. This is also diagrammatically illustrated in Fig. 6 of the drawings. 120

The forward bearing 53 of the tail-stock 50, as has been stated, is slidably sustained 125

on the reciprocating rod 54, and a spring 69 is coiled on said rod and is compressed between the movable bearing 53, and the stationary bearing 26 or 27 as the case may be.

By this means the spring 69 constantly tends to push the movable tail-stock bearing on the rod 54 in a direction that would separate the tail-stock from the head stock, but the hook 65, on pivoted dog 62, normally holds the tail-stock against this lateral displacement.

The trip-lever 57 and its trip-finger 68 normally, during the winding operation, have the positions shown in the top view in Fig.

15 7 and the trip-dog 62 with its hook 65 holds the tail-stock against the action of the spring 69. This condition prevails until the trip-finger 68, is pushed outwardly by the wound yarn on the bobbin, at which moment it is 20 desired to release the tail-stock 50 and allow it to move laterally so as to release the filled bobbin. This release operation of the tail-stock is effected by the withdrawal of the hook 65 on the trip-dog and the movement 25 of the dog is caused by means which will now be explained, reference being made particularly to Figs. 2—7—8 and 9 of the drawings.

To the horizontal bar 28 I attach a plurality of bearing brackets 70, and these brackets carry a reciprocating rod 71 that extends horizontally throughout the width of the machine. The means for reciprocating this rod 71 will presently be explained.

35 The rod 71 extends horizontally across the front of the machine and past the several winding units, and at each winding unit I provide a clamp-bracket 72, on the rod. Each clamp-bracket is provided with a pawl 73, 40 whose upper end is pivoted to the bracket and whose lower end 74 hangs pendants and normally slides on top of the straight-edge side 61 of the trip-lever 57, as it is carried back and forth in a horizontal direction with 45 the reciprocating rod 71. As long as the lever 57 is in the normal position so the lower end of the pawl can slide thereon, the latter will simply slide over said edge 61 and ride over the trip-end 63 of the dog. When, however, 50 the lever 57 is tripped and moved to the position shown in Figs. 8 and 9 of the drawing, the lower end 74 of the pawl will drop down upon the top surface of the bar 28 because the lever 57 has been swung laterally from beneath the pawl.

When the pawl-end 74 drops down onto the bar 28, and it makes its next movement with clamp 72 toward the head-stock 46, it, 60 the pawl, will engage the trip-end 63 of the dog 62, and push said dog-end inwardly over the bar 28, thereby swinging the hook-end 65, from engagement with the tail-stock and thus release the latter so the spring 69, can throw the tail-stock laterally until the bearing 53 of said tail-stock strikes the stationary

collar 75 that is fixed on the reciprocating rod 54, as clearly shown in Figs. 8 and 9 of the drawings.

When the tail-stock 50 has been moved laterally, it carries the arm 55 with it because 70 the latter is attached thereto and as the cutter-blade 56 is carried by said arm, this blade will also be given a sudden lateral movement in order that it may sever the yarn and entirely free the bobbin.

75 Each winding unit is provided with a hopper in which a series of empty bobbins are stored so that when one bobbin has been re- 80 volved in the chuck, and the required quantity of yarn wound thereon, it will be released through the action of the trip-lever, dog and movable tail-stock and discharged into a chute 76, which leads to a trough or receptacle 77 in which the filled bobbins are 85 collected.

The hoppers 78, are sustained on the tie-rods 43 and 79 and have an inclined position with their lower ends terminating adjacent to lifter arms which will now be explained.

At said lower hopper-ends I provide two 90 lifter-arms 80 each of which has a concave upper end 81 which extends beneath the lowermost bobbin 82 in the hopper, as shown in broken lines in Fig. 3 of the drawings. These concave ends 81 of the lifter-arms are 95 off-set or extend forwardly from the curved rear faces 83 of said arms, and by reference to said Fig. 3 it will be seen that said ends are so off-set that they will form a support for the lowermost bobbin while the curved 100 rear-faces 83 of the arms extend through an arch which, if extended, would pass between said lowermost bobbin and the empty bobbin next above it. The reason for this is that as the arms 80 are swung up, as will presently be explained, to lift the lowermost bobbin from the chute up to a position to be engaged by the chucks, the curved faces 83, of the arms will engage the second bobbin and prevent it, and the bobbins in the chute above 105 it, from dropping down until the arms 80 have again been lowered.

110 The lifter arms 80 are each carried on an up-turned end 84 of a lifting lever 85. These levers 85 have clamps 86 at their ends which 115 clamps rigidly engage a sleeve 87 that is loosely carried on a horizontal rock-shaft 88. This rock-shaft 88 also extends throughout the width of the machine and is continuously rocked by means that will presently be explained, but the arms will only swing under certain conditions as will also presently be explained.

120 The lifter-arms 80 are pivotally attached at 89 to the ends 84 of the levers 85 and an 125 adjustable stop-screw 90 is carried by the levers whereby the lower ends of the arms 80 may, by engaging said stop-screws, be adjusted as to their normal positions and thus accurately determine the positions for the 130

concave upper ends 81 of said arms to best deliver the empty or partly empty bobbins into the chuck.

5 A spring 91 engages the lower end of each arm 80 and yieldingly draws the lower end thereof toward the stop-screw.

10 By reference to Figs. 3—4 and 6 of the drawings, it will be noted that one of the levers 85 of each winding unit is provided with a notch 92 in its upper side and that a latch-bar 93, is pivotally attached at its upper end to a lug 94 that depends from the movable tail-stock 51 and has its lower end engaged in said lever-notch 92. A spring 95, engages 15 the latch-bar 93 and merely braces the lower end thereof to prevent the same from swinging loosely.

20 To each unit, comprising the two lifter-levers 85, there is attached a coiled spring 96 of sufficient strength to lift the levers 85, arms 80 and to turn the sleeve 87 on the shaft 88, during such lifting operation. These 25 levers and arms however are held down against the pull of the spring 96 and in the positions shown in Fig. 3—4 and 6, by the latch-bar 93 engaging one of the levers.

On the end of the sleeve 87, I provide a 30 clamp-head 97 (see Figs. 4—6 and 8 of the drawings) and from one side of this head there projects a pin 98, that extends horizontally and in a direction parallel with the shaft 88.

35 At one side of but spaced from the head 97, there is a collar 99 on the shaft 88, which collar is rigid on the shaft and oscillates as the shaft 88 is rocked. This collar is provided with a pin 100 which projects from one side thereof and in a direction toward the clamping-head 97 and the pin 100 on the 40 collar and the pin 98 on the head lap.

45 The positions of these two pins 98 and 100 are the same with respect to the axis of the shaft 88, but when the levers 85 are in the normal position and the arms are supporting the row of bobbins 82 as in Fig. 3, these pins are separated sufficiently to permit the shaft 88, collar 99 and its pin 100, to oscillate or rock without the pin 100 engaging the pin 98, but these pins will be brought into engagement when the arms 80 have been swung up 50 to deliver an empty bobbin to the chuck, so that said arms will be returned against the lifting action of the spring 96. This will also presently be more clearly explained.

55 It has hereinbefore been stated that shaft 88 continuously rocks back and forth and that rods 54 and 71 continuously reciprocate.

60 The means for effecting these operations will therefore now be explained, reference being made particularly to Figs. 2—5 and 6 of the drawings.

65 The central horizontal shaft 41 which extends fore and aft of the machine carries a heart-shaped cam 102. At the front of this cam I provide a horizontal rod 103, which is

supported in the bearing-plates 27 and on this rod there is a slidable frame having a horizontal bar 104 and a central upright slotted bar 105. This frame is simply slidable horizontally on the rod 103 which serves as a guide for the same.

The bar 104 carries two rollers 106 and 107 which are located at opposite sides of the cam 102 so that as the cam revolves first one roller and then the other will be engaged and the bar 104 thereby be constantly reciprocated.

In front of the bars 104 and 105 there is provided a vertical slotted bar 108 whose lower end is mounted on a horizontal pin 109 that has bearing in a block 110 beneath the worm-shaft 38, as best shown in Fig. 5 of the drawings.

Obviously, as the cam 102 reciprocates bar 104, the bar 108 will be swung back and forth.

The upper end of this bar 108 is attached to a block 111 which is carried on the horizontal rod 71,—the attachment being made by a pin 112 extending through the slot of bar 108 and as vertical bar 108 swings back and forth it imparts a reciprocating movement to the rod 71, for a purpose that will presently be explained.

At the rear of the worm gear 40, the central shaft 41 carries a pear-shaped cam 113. This cam has position directly beneath the rod 54, and two arms 114 depend from said rod 54 at opposite sides of the cam 113 so that said cam will engage one of said arms to move rod 54 in one direction and will then engage the other arm to move the rod in a reverse direction.

The rod 54 is therefore reciprocated horizontally and continuously, through the bearing plates 26 and 27, and also through the bracket 51 of the tail-stock,—the latter being held against the expansion of the coiled spring 69 by means of the hook 65, during the winding of the bobbin 82 that is held between the head-stock 46 and the tail-stock 50.

Behind the pear-shaped cam 113 I provide another cam 115 on the shaft 41. This cam revolves with its periphery in close proximity to a roller 116 that is mounted on an arm 117 which arm is mounted on and extends rearwardly from the shaft 88.

The worm-gear 40, and cams 102—113 and 115 are all secured together by pins 37 (see broken lines in Fig. 5) which extend horizontally therethrough, which maintains them in proper operative relation.

During the winding of the yarn on the bobbin it is desirable that the yarn be given a traverse motion between the opposite ends of the bobbin and with this in view I attach to the reciprocating or traverse rod 71 a block 118,—one of these blocks being provided at each winding unit immediately above the bobbin-space between the two chucks. Each block 118 carries a yarn-guide

119 having the form of wire arms with a slot between them for the passage of the yarn down to the bobbin.

It is believed to be obvious that as the rod

5 71 reciprocates in a direction parallel with the axis of the bobbin that the yarn-guides 119 will be given a traverse motion, carrying the yarn with it, so the latter will be fed to the bobbin uniformly from end to end.

10 Another desirable feature provided in my machine lies in the fact that in case the yarn 16 should break I provide means whereby the tail-stock 50 will be released, the bobbin discharged and a new bobbin immediately fed 15 between the chucks.

The means for effecting this operation will therefore now be explained, reference being made particularly to Figs. 3—6—7—8 and 9 of the drawings.

20 To the side of each traverse block 118 on the rod 71, I pivotally attach a plate 120 so that the plate will move with the block 118 and shaft 71 but may swing in addition to its traverse movement. This plate 120 carries 25 a wire trip-arm 121 which extends upwardly and rearwardly and has a horizontal stretch 122 which lies against the downwardly-traveling yarn thread 16, as best seen in Figs. 3 and 6. The thread of yarn therefore 30 holds the trip-arm 121 up.

The lower end of the pivoted plate 120, carries a wire finger 123 which extends laterally, downwardly and rearwardly therefrom.

35 From the end of the trip-lever 57, there projects an arm 124 and this arm turns laterally and has position adjacent to the wire finger 123 of plate 120.

In case the yarn 16 breaks, the wire trip-arm 40 121 will drop down, as shown in broken lines in Fig. 3 which causes the plate 120 to swing the wire finger 123 forwardly against the arm 124, and move the latter forwardly. When arm 124 is thus moved forwardly it 45 pulls one end of the trip lever 57 forwardly and swings the straight edge side 61 of said lever rearwardly so as to allow the pawl 73 to drop down on bar 28.

Then as the pawl 73 makes its forward 50 stroke it engages the trip 63 on the dog 62 and withdraws the hook 65 from engagement with the tail-stock, just as it would do if trip-finger 68 were operated by the filled bobbin, and the tail-stock then moves laterally and 55 drops the bobbin from between the chucks.

Having described the construction and arrangement of the mechanisms, a brief explanation of the operation is believed to be desirable.

60 The operator or attendant will first lead the strands of yarn from the supply over the guides 20 and tension-disks 23 and then carry them down to the bobbins 82 in the inclined chute 78,—attaching one strand to each of 65 the empty or partly empty bobbins.

Having thus connected a strand of yarn 16 with the several bobbins, one bobbin at each unit will be automatically placed between the head and tail stocks when the machine is started.

As the bobbin is revolved by the belt-driven pulley 47 on the head-stock the yarn will be wound thereon, during which operation the yarn guide 119 is caused to traverse over the bobbins and distribute the yarn 75 thereon.

When the yarn on a bobbin has reached a sufficient diameter, it will press against the trip 68, and push the latter forward carrying one end of lever 57 with it and swinging 80 the opposite end of said lever rearwardly.

During this winding operation the rod 71 is constantly reciprocating causing a pawl 73 at each unit to travel back and forth over the edge of the lever 57. When this lever is moved however by the yarn on the filled bobbin, this pawl 73 will drop down and when it is carried back it will engage the trip-end 63 of the dog and withdraw the catch or hook 65 from the tail-stock 50, whereupon the coiled spring 69 will throw the tail stock laterally, release the filled bobbin and at the same time the cutter 56 will sever the yarn from the released tail-stock.

As the tail-stock 50 is released and moved laterally, the latch-bar 93 is disengaged from the lifting levers 85 and the latter are drawn up by the spring 96.

These levers carry the lifter arms 80 which raise the lowermost bobbin from the chute and lift it to a position between the chucks or head and tail stocks.

When the levers 85 swing up, the sleeve 87 on shaft 88 will have been turned and the pin 98 on clamp 97 will also be turned so that as the shaft 88 makes its next partial rotation through the cam 115, roller 116 and arm 117, the pin 100 on the collar will engage pin 98 on the clamp and swing said clamp in a direction that will lower the levers 85 and arms 80 to their normal position.

Just before the return movement of the levers 85 and arms 80, shaft 54 will be reciprocating in a direction that will cause the collar 75 thereon to engage the movable tail-stock and push it back so as to engage the empty bobbin and when it engages the bobbin the arms 80 return or lower, catch 65 engage the stock and latch-bar 93 will again engage the levers 85 and hold them down and the operation is repeated on the next bobbin.

Having described my invention, I claim,—

1. In a machine of the character described the combination with chuck-members for holding a bobbin, means for operating the chuck members automatically to engage the bobbins as presented, means for retaining a plurality of empty bobbins with the yarn connected thereto and means for presenting them to the chucks, of means for rotating the 125 130

- bobbin to wind yarn thereon from a strand, and means for releasing and discharging the bobbin upon the breaking of the strand.
2. In a machine of the character described 5 the combination with two chuck members one of which is movable with respect to the other and between which a bobbin may be held of means for rotating one of said chuck-members to revolve the bobbin and wind yarn 10 thereon, a spring tending to move the movable chuck member away from the other chuck member, means for locking the movable chuck member against the tension of the spring in bobbin holding position, means 15 actuated by the yarn on the bobbin for releasing the movable chuck-member to discharge the bobbin with the wound yarn thereon and means for placing an empty bobbin between the chuck-members.
- 20 3. In a machine of the character described the combination with two chuck-members to hold a bobbin, of means for movably sustaining one member with respect to the other, means for rotating one of said members to 25 revolve the bobbin and wind yarn thereon from a strand, means actuated by the yarn on the bobbin for releasing the movable chuck-member, means carried by the moving chuck member for severing the strand as the 30 bobbin is released and means for feeding an empty bobbin between the chuck-members.
4. In a machine of the character described the combination with two chuck-members one of which is movable toward and from the 35 other and between which a bobbin may be held of means for rotating the bobbin to wind yarn thereon, a spring tending to move the movable chuck member away from the other chuck member, means for locking the 40 movable chuck member against the tension of the spring in bobbin holding position, means actuated by the yarn on the bobbin for releasing the movable chuck-member, means for feeding an empty bobbin between the chuck-members and reciprocating means for returning 45 the movable chuck-member to engage the empty bobbin.
5. In a machine of the character described the combination with two chuck-members 50 one of which is movable toward and from the other and between which a bobbin may be held of means for rotating the bobbin to wind yarn thereon, latch means for engaging the movable chuck-member to hold it with 55 respect to the other chuck-member, means operated by the yarn on the bobbin to release the latch and allow the movable chuck-member to move and discharge the bobbin, and means for feeding an empty bobbin between 60 the chucks.
6. In a machine of the character described the combination with two chuck-members, of means tending to press one chuck-member away from the other, latch means to hold the 65 chuck-members in engagement with a bobbin to wind yarn thereon from a strand, and means for releasing and discharging the bobbin upon the breaking of the strand.
- bin, means for automatically actuating the latch-means to separate the chuck-members and discharge a bobbin therefrom and reciprocating means for returning the movable chuck-member to receive another bobbin.
7. In a machine of the character described 70 the combination with two chuck-members at least one of which is movable,—said chuck members being adapted to hold a bobbin, of means for rotating the bobbin to wind yarn 75 thereon, means for automatically actuating the movable chuck-member to release the bobbin therefrom and means controlled by the movable chuck-member for feeding an empty bobbin between said members.
8. In a machine of the character described 80 the combination with a movable chuck-member, of a stationary chuck-member said two members being adapted to hold a bobbin, means for rotating the bobbin to wind yarn 85 thereon, means for automatically actuating the movable chuck-member to release the bobbin, a hopper for holding empty bobbins, transfer means movable between the hopper and the chucks and means controlled by the 90 movable chuck for effecting an operation of the transfer means.
9. In a machine of the character described 95 the combination with two chuck-members at least one of which is movable,—said chuck members being adapted to hold a bobbin, of means for rotating the bobbin to wind yarn thereon, means for automatically actuating the movable chuck-member to release the bobbin therefrom, means controlled by the 100 movable chuck-member for feeding an empty bobbin between the chucks and reciprocating means for returning the movable chuck to engage the empty bobbin.
10. In a machine of the character described 105 the combination with two chuck-members adapted to hold a bobbin, of means for rotating the bobbin to wind yarn thereon, means actuated by the yarn or the bobbin to release one of the chuck-members, means for moving 110 said released member to free the bobbin, a rock-shaft, transfer means carried on the rock-shaft to feed an empty bobbin between the chucks and reciprocating means for returning the movable chuck to engage the 115 empty bobbin.
11. In a machine of the character described 120 the combination with two chuck-members to carry a bobbin,—one of said members being movable with respect to the other, a spring tending to move the movable chuck member away from the other chuck member, means for locking the movable chuck member against the tension of the spring in bobbin holding position, two reciprocating rods, a 125 traverse device operated by one of said rods, means for automatically shifting the movable chuck-member to release a filled bobbin, means coacting between the other reciprocating rod and the movable chuck-member to 130

- restore the latter to the bobbin-engaging position and means for automatically feeding an empty bobbin between the chuck-members.
12. In a machine of the character described 5 the combination with two chuck-members to carry a bobbin,—one of said members being movable with respect to the other, two reciprocating rods, a traverse device operated by one of said rods, means for automatically shifting the movable chuck-member to release a filled bobbin, means coacting between the other reciprocating rod and the movable chuck-member to restore the latter to the bobbin-engaging position, a rock-shaft and bobbin-feeding means mounted on the rock-shaft.
13. In a machine of the character described 10 the combination with two chuck-members one movable with respect to the other and said members being designed to hold a bobbin, yielding means for constantly exerting a pressure on the movable chuck-member in a direction away from the other member, means for locking said movable chuck-member 15 against movement by the yielding means, trip means for automatically releasing the locking-means and permit the chuck-member to move and release the bobbin, a rock-shaft, bobbin-feeding means carried by the rock-shaft means controlled by the movable chuck-member for actuating the bobbin-feeding means and means for returning the movable chuck-member to the bobbin-engaging position.
14. In a machine of the character described 20 the combination with two chuck-members to carry a bobbin and one of said members being movable with respect to the other of means for rotating the bobbin to wind yarn thereon, means for automatically ejecting the bobbin with yarn thereon, a rock-shaft, arms carried on the rock-shaft and movable in one direction independently of said shaft said arms serving to carry an empty bobbin to the chuck-members and means for engaging the arms with the rock-shaft to effect their movement in the other direction.
15. In a machine of the character described 25 the combination with two chuck-members to carry a bobbin and one of said members being movable with respect to the other of means for rotating the bobbin to wind yarn thereon, means for automatically ejecting the bobbin with yarn thereon, a rock-shaft, arms carried on the rock-shaft and movable in one direction independently of said shaft said arms serving to carry an empty bobbin to the chuck-members means for effecting an adjustment of the arms with respect to the rock-shaft and the chuck-members and means for engaging the arms with the rock-shaft to effect their movement in the other direction.
16. In a machine of the character described 30 the combination with means for holding and revolving a bobbin to wind yarn thereon, of means for holding empty bobbins, a rock-shaft, arms carried on the rock-shaft and movable in one direction independently of said shaft, means for adjusting said arms with respect to the empty bobbin holder and 35 the bobbin revolving means and means on the rock-shaft to coact with said arms to move the latter in the other direction by said rock-shaft.
17. In a machine of the character described 35 the combination with means for holding and revolving a bobbin to wind yarn thereon, of means for holding empty bobbins, a reciprocating rod, a trip device carried by the rod to engage the strand of yarn leading to the 40 bobbin and means actuated by the trip device for releasing the holding and revolving means when the yarn strand breaks.
18. In a machine of the character described 40 the combination with a plurality of bobbin-holding and revolving units, of separate 45 yarn-feed means for each unit, independent bobbin-discharge means for each unit, means common to a plurality of the units for resetting the discharge means thereof, and means 50 for feeding empty bobbins to each unit.
19. In a machine of the character described 50 the combination with a plurality of bobbin-holding and revolving units, of separate 55 yarn-feed means for each unit, independent bobbin-discharge means for each unit, means common to a plurality of the units for resetting the discharge means thereof, a bobbin-feeding means for each unit, independent 60 means for moving the bobbin-feeding means of the units in one direction and means common to a plurality of the units for actuating the several bobbin-feeding means in the other direction.
20. In a machine of the character described 60 the combination with a plurality of bobbin-holding and revolving units, of separate 65 yarn-feed means for each unit, independent bobbin-discharge means for each unit, means common to a plurality of the units for resetting the discharge means thereof, a bobbin-feeding means for each unit, independent 70 spring means for moving each bobbin-feeding means in one direction and a rock-shaft common to a plurality of the units for operating 75 the several bobbin-feeding means in the other direction.
21. In a machine of the character described 75 the combination with a plurality of bobbin-holding-units, of means for revolving the 80 bobbins, means for feeding a strand of yarn to each unit, independent means for each unit to discharge a filled bobbin therefrom, means common to all the units resetting the holding 85 means of each of them, independent means for feeding empty bobbins to each unit and independent trip-means for discharging a 90 bobbin of a unit when the yarn breaks.
- In testimony whereof I affix my signature.
- FRANCIS A. LAZENBY.
